SWEAT BAND FOR FELT HATS

John Cavanagh, East Norwalk, Conn., assignor to
 Hat Corporation of America, East Norwalk,
 Conn., and New York, N. Y., a corporation of
 Delaware

Application July 7, 1933, Serial No. 679,349

5 Claims. (Cl. 2—181)

This invention has reference to hats such as are made of fur or the like, and designed for both men's and women's wear, and more particularly relates to an improved form of sweat band applied to the underside of the brim and extended into the crown of the hat.

With the present method of attaching sweat bands to felt hats, and wherein the edge of the sweat band terminates and is stitched to the hat body at the junction of the inner side of the crown and brim, hats, including their silk bands, are very liable to become soiled with the perspiration from the head, by reason of the fact that as the sweat band becomes wet from the perspiration, the sweat flows down, passes through the rows of needle holes or over the edge of the sweat band, and onto the body of the hat, which it quickly penetrates and is quickly conveyed to the silk hat band, on the outside, in a way to dampen and discolor the same, and with the further result that as the hat again dries, the oil and salt of the sweat is left on the hat body and silk band, giving them a soiled and objectional appearance.

It is therefore with a view of overcoming these objections that I have sought to provide a sweat band for felt hats which will be as near sweat-proof as can be commercially made, and which in practice, I find, very materially prolongs the usefulness of hats of this class.

An object of the invention is to provide a composite sweat band of improved construction and materials which will better serve to effectively divert and absorb the perspiration from a wearer's head in a manner to prevent it from soaking through the sweat band and thus soiling the hat body and hat band encircling the outside of the hat.

In the carrying out of my invention, I preferably use an outer annular member that may be formed of leather or other suitable material, and flange the lower edge portion by deflecting it outward with respect to the annular band portion of the hat, and stitch its edge to the under surface layer of felt, of which the brim is formed, so that the needle and thread does not go through the brim in a manner to be exposed on the top side thereof, as is usually the case in the manufacture of straw hats.

I preferably not only flange or extend the edge portion of the sweat band out under the brim away from the critical point, so to speak, the junction of the crown and brim, but I provide additional preventative means intermediate of the sweat band and the hat body to prevent any

perspiration which might possibly work through the leather from contacting with the hat body and hat brim.

The invention accordingly consists in the features of construction and arrangement of parts which will be exemplified in the illustrations hereinafter described and the scope of the application of which will be indicated in the following claims.

In the accompanying drawing in which is shown one or more possible embodiments of my invention.

Fig. 1 shows a bottom plan view of a felt hat having one of my improved sweat bands attached thereto;

Fig. 2 is a vertical cross sectional view, broken away, through one side of the hat shown in Fig. 1;

Fig. 3 is a fragmentary perspective view of a portion of the exposed member of the sweat band shown in Fig. 2; and

Fig. 4 shows a sectional view through the band portion of a hat somewhat like that shown in Fig. 2, though comprising a modified assemblage.

In the old method of attaching sweat leathers or sweat bands to felt hats, the perspiration from the wearer would work down to the line of stitches along its lower edge portion, which in turn would serve as a wick to conduct the perspiration through the needle holes to the felt body in a way to dampen and soil the same more or less according to the amount of perspiration and the conditions under which the hat was worn. I have now devised a perspiration-proof sweat band, as will now be referred to in detail, having an outwardly disposed annular flange extended from its lower portion which serves to protect both the inner wall of the band portion and the under wall or surface of the brim to a limited extent sufficient to prevent the perspiration from working across the flange and onto the brim.

Referring in detail to the characters of reference marked upon the drawing, 5 represents the top of the crown of a felt hat, 6 the annular side wall of the crown, and 7 the brim. In this connection it will be understood that the hat as well as the brim may be formed of any suitable material, as for instance fur, and may be of any preferred style or shape, as the object of the invention is to protect all types of hats wherein the perspiration is liable to penetrate and soil the band and brim portion of the body. 8 represents the band portion of the hat body which, in this instance for clearness, is not shown as being provided with a hat band.

9 represents the outer annular member of my

- improved sweat band which may be formed of leather or other suitable material, and has its lower edge portion deflected outward to form an annular flange 10 which conforms to the shape of the inner wall of the side crown and the underside of the brim, the said member being secured to the brim by having its outer annular edge portion 11 sewed to the outer layer of fur of the underside of the brim without allowing the threads 12 to extend through to the top side, and whereby the said threads are carried over the outer annular edge of the flange in a way to draw it in against the brim and form a neat finish to the underside of the brim.
- 15 Next adjacent to the inner side of this annular flanged member 9, I provide an intermediate band of absorbent material 13 such as felt, cotton or the like, and between it and the hat body I also provide a strip of oiled silk, rubber or other water-proofing material 14, as shown in Fig. 2, which like the outer member 9 and absorbent material 13, includes a flange 15, the edge 16 of which is sewed in between the edge 11 of the outer member and the underside of the hat brim, and whereby any dampness which may penetrate the member 9 will contact with and be distributed by the absorbent material 13, thus lessening its possible damaging effect on the hat body. With the inclusion of water-proof material 14 between the absorbent material and the hat body, all possibility of the soiling of the latter is eliminated.
- 20 In Fig. 4 I have shown a form of sweat band embodying my invention which includes the flanged strip of absorbent material 13 positioned between a folded strip of leather or other suitable material comprising the outer flanged member 9^a and the inner flanged member 14^a, which in this instance are formed of the one piece, and folded longitudinally to form the closed annular upper edge portion 17. In this case, this latter mentioned portion 14^a would preferably be coated with a non-absorbent material such as rubber, cellophane or the like, and in this connection I secure the raw edge portions of the three layers together, as at 18, by cement or a line of stitching, the threads of which would be treated with water-proof material to prevent absorption of perspiration which may come in contact therewith.
- 25 This ensemble, thus produced, represents a commercial article of manufacture which may either be made up or purchased by hat manufacturers and by them stitched into hat bodies by a shallow form of stitching. The thicknesses of the materials as shown in Figs. 2 and 4, are somewhat exaggerated for the sake of clearness.
- 30 In addition to the protective qualities of the sweat band herein described, it will also be seen that a very much more comfortable hat to wear is produced, and one that will set closer to the head.
- 35 Having thus described my invention, what I claim and desire to secure by Letters Patent is:

1. In combination, a hat including a crown and brim portion, an outer annular band positioned within the crown and having an outwardly disposed annular flange conforming to the undersurface of the brim, an inner strip of absorbent material also having an outwardly disposed annular flange and positioned between the outer annular band and the body of the hat, the edges of the flanges being sewed to the undersurface of the brim by stitches passing through the flanges, over the edges, and through the undersurface of the brim in a manner to not show on the top surface of the brim. 80
2. In combination, a hat including a crown and brim portion and an annular outer band positioned within the crown and having an outwardly disposed annular flange conforming to the undersurface of the brim, the edge of the flange being sewed to the undersurface of the brim by stitches passing through the flange, over the edge, and through the undersurface of the brim in a manner to not show on the top surface of the brim, and a flanged water-proof protective member intermediate the hat body and outer band having its outer edge portion secured between the undersurface of the brim and the flanged portion of the sweat band and secured by the stitches attaching the outer band to the brim. 85
3. In combination, a hat including a crown and brim portion and an annular outer band positioned within the crown and having an outwardly disposed annular flange conforming to the undersurface of the brim, the edge of the flange being sewed to the undersurface of the brim by stitches passing through the flange, over the edge, and through the undersurface of the brim in a manner not to show on the top surface of the brim, a strip of absorbent material adjacent the said band and a strip of water-proof material between the absorbent material and the hat body and having its outer edge portions secured between the undersurface of the brim and the flanged portion of the outer band, and secured by the stitches attaching the outer band to the hat. 90
4. As a new article of manufacture, a sweat band comprising a strip of absorbent material and a strip of water proof material, each having an outwardly disposed annular flange portion to conform to the undersurface of a hat brim, the edges of said flanges being secured together to form an assembled sweat band adapted to be set into a hat. 95
5. As a new article of manufacture a sweat band comprising a leather band, a strip of absorbent material and a strip of water proof material, each having an outwardly disposed annular flange to conform to the undersurface of a hat brim, the edges of said flanges being secured together to form an assembled sweat band. 100
